US0D1043633S

(12) **United States Design Patent** (10) **Patent No.:** **US D1,043,633 S**
(45) **Date of Patent:** **** Sep. 24, 2024**

(54) **TV BRACKET**

(71) Applicant: **Shenzhen Haibi Trading Co., Ltd.**,
Shenzhen (CN)

(72) Inventor: **Jichen Deng**, Shenzhen (CN)

(***) Term: **15 Years**

(21) Appl. No.: **29/929,638**

(22) Filed: **Feb. 23, 2024**

(30) **Foreign Application Priority Data**

Sep. 1, 2023 (CN) 202330565590.2

(51) **LOC (14) Cl.** **14-03**

(52) **U.S. Cl.**

USPC **D14/239**

(58) **Field of Classification Search**

USPC D14/125, 126, 238, 239, 336, 371, 374,

D14/375, 376, 377, 448, 451; D19/113,

D19/114; D6/328, 332

CPC F16M 11/10; F16M 11/24; F16M 11/00;

F16M 13/02

(57) **CLAIM**

The ornamental design for a TV bracket, as shown and described.

DESCRIPTION

FIG. 1 is a top perspective view of a TV bracket, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view thereof shown with environment.

The broken lines in the drawings illustrate the portions of the TV bracket, which form no part of the claimed design.

1 Claim, 9 Drawing Sheets
